UNITED STATES PATENT OFFICE.

ARTHUR D. COCHRAN, OF INDIANAPOLIS, INDIANA.

STREET-CAR CURTAIN.

SPECIFICATION forming part of Letters Patent No. 474,902, dated May 17, 1892.

Application filed February 15, 1892. Serial No. 421,547. (No model.)

To all whom it may concern:

Be it known that I, ARTHUR D. COCHRAN, of Indianapolis, county of Marion, and State of Indiana, have invented certain new and useful Improvements in Street-Car Curtains; and I do hereby declare that the following is a full, clear, and exact description thereof, reference being had to the accompanying drawings, in which like figures refer to like parts.

10 My invention relates to new and useful improvements in street-car curtains, and to one that is especially adapted for use on open or summer cars, and will be understood from the following description.

15 In the drawings, Figure 1 is a side view of a part of a car, showing one of my curtains drawn down and parts of two others. Fig. 2 is a vertical section of the same on the line *w w*, Fig. 1, showing the curtain thrown up. Fig. 3 is an enlarged sectional view on the line *x x*, Fig. 1, showing the lower part of the curtain, it being drawn down. Fig. 4 is a cross-section on the line *y y*, Fig. 1. Fig. 5 is a cross-section on the line *z z*, Fig. 3. Fig. 6 is 25 a side view showing the connections of the curtain to the lower stiffening-wire, and Fig. 7 shows a plan and edge view of the bottom stiffening-wire.

20 In detail, 1 is the frame-work of a street-car, 2 the seats, and 3 the connecting uprights. These uprights, as shown in Figs. 4 and 5, have semicircular grooves 4 on opposite sides, and at the bottom of each a block or casting 5 is set, in which the lower end of the vertical rod or wire 6 is placed and retained in position by a set-screw 7, the rods 6 extending upward and nearly to the top of the uprights and just above the guide-wheels 8, mounted in brackets 9, secured to the uprights 3 on either side of the rod 6.

25 10 is the curtain, which is attached to any ordinary spring-roller supported within the car, as shown at 11, and the curtain passes over the idler-roller 12, in line with the vertical rods 6. The curtain 10 is formed bylapping over its sides and stitching the same together, the lower ends being secured at each side around the rings 13, formed on either end of the stiffening-wire 14, the cloth or curtain material being held in place by the wires 15, which press the material into the grooves 16, formed in the rings or loops 13, these wires

passing through small holes 17 in the wire 14, as shown in Fig. 7. The curtain thus formed is secured in place by slipping the two rings 13 over the tops of the vertical rods 6, the brackets 9, with their guide-wheels 8, being afterward put in place. The curtain can then be moved up or down upon the rods, being guided by them, and at the same time the guide-wheels 8 prevent the rods 6 from being strained or pulled out of place, and the wire loops 15 around the rings at the bottom of the curtain prevent any frictional contact with the curtain material, so that the curtain is not easily worn or injured by tearing.

30 18 is a rubber stop pivoted on the inside of one of the uprights 3, as shown in Figs. 2 and 3, and is for the purpose of holding the curtain in its lowest position when drawn down, and should at any time the curtain be pushed up by any one not experienced in its use the rubber stop would contract and allow this to be done. At the same time its strength is entirely sufficient to prevent the curtain from being thrown up by any sudden jolt or jar of the car. The advantage of this curtain over the ones ordinarily in use is that there is no space left at either side by which rain or air can penetrate into the car, and the construction and operation of the curtain is so simple that it is not likely to get out of order, as is the case with ordinary curtains. Should at any time either of the vertical rods 6 be bent or broken, the set-screw 7 in the socket-block 35 5 can be loosened and the old rod readily taken out and a new one put in place.

35 What I claim as my invention, and desire to secure by Letters Patent, is the following:

40 1. In a street-car curtain, suitable uprights having vertical grooves on their opposing faces, vertical rods removably seated at the base of such grooves, a curtain supported from a spring-roller above such rods, the sides of such curtain hemmed around the vertical rods, the bottom of such curtain attached to a horizontal wire having loops fitting around the upright rods, such rods held in a vertical position at their top by means of guide-wheels, which bear on the curtain, substantially as 45 shown and described.

45 2. A street-car curtain suspended from a suitable roller, its two sides hemmed, and its lower edge secured to a wire having rings at

either end, such rings and the hem of the curtain adapted to work upon vertical rods within the grooved faces of suitable uprights, such rods retained in their vertical position 5 by means of guide-wheels, which bear on opposite sides of the curtain outside of the rods, such wheels mounted in brackets connected to the uprights and a guide-wheel at the top of such rods, and a catch at the lower end for 10 holding the curtain in a lowered position, substantially as shown and described.

3. A curtain suspended from a suitable roller, the sides of such curtain hemmed, its 15 lower edge attached to a stiffening-wire having rings or loops on its outer ends, such rings and the hem of the curtain adapted to work up and down on vertical rods suitably connected to the frame-work of a car at their base, their upper ends retained in a vertical 20 position by guide-wheels, which bear against the curtain outside of the rods, substantially as shown and described.

4. A street-car curtain suspended from a suitable roller, the sides of such curtain

hemmed, a stiffening-wire attached to its lower 25 edge, rings formed on the ends of such wire having grooves in their faces, the side hems of the curtain fitting over such rings and retained in position by suitable locking-wires, such rings and hems adapted to work over 30 vertical rods suitably supported at their base in grooves formed in uprights, the tops of such rods retained in position by bearing-wheels, which contact with the curtain outside of the rods, a guide-roller above the top 35 of such rods, and a rubber catch near the bottom pivoted to one of the uprights and adapted to contact with the stiffening-wire of the curtain, whereby the curtain is retained in a lowered position, substantially as shown and 40 described.

In witness whereof I have hereunto set my hand this 11th day of February, 1892.

ARTHUR D. COCHRAN.
